UNITED STATES PATENT OFFICE.

ISIDOR ROTH, OF BROOKLYN, NEW YORK, ASSIGNOR TO BENJAMIN & JOHNES, A CORPORATION OF NEW JERSEY.

HOSE SUPPORTER.

Application filed June 8, 1927. Serial No. 197,276.

This invention relates more particularly to hose supporters such as are applied to corsets, brassières and combination garments and depend therefrom to be attached to the 5 stockings. Such hose supporters are usually made adjustable in length, and it has been common to employ for this purpose buckles which present themselves more or less at the front of the hose supporter and are objectionable with light, thin dresses in that they protrude so as to be unsightly and also cause undue friction and wear.

The objects of this invention are to secure a hose supporter which shall be longitudinally adjustable and yet present an unbroken extent of webbing at the front, with the adjusting means at the back of and concealed by said webbing; to thus secure an improved appearance and cover the adjusting means against rubbing upon or wearing the outer garment or dress; to secure a stronger and more durable hose supporter, and to obtain other advantages and results as may be brought out by the following description.

Referring to the accompanying drawings, in which like numerals of reference designate the same parts throughout the several views,

30 Figure 1 is a front view of a hose supporter embodying my invention, with a portion of the same broken away and showing part of a garment from which the hose supporter depends;

35 Figure 2 is a rear or inner view of the same;

Figure 3 is a longitudinal section on line 3—3, Figure 1, and

40 Figure 4 is a detail view of a certain wire connecting member.

In the specific embodiment of the invention shown in said drawings, 1 indicates a lower edge portion of a garment from which a hose supporter is adapted to depend, and 45 2 indicates a fabric loop projecting from the lower edge of the garment to receive the upper bar of a wire loop 3, to the lower bar of which the preferably elastic webbing 4 of the hose supporter is secured, as by looping around said bar and stitching at 5, see 50 Figure 3. This webbing 4 extends downwardly to the desired length and is then turned rearwardly upward, forming an end portion 6 to which is stitched or otherwise 55 suitably secured a piece of webbing 7 which

is narrower than the front webbing 4. This narrow rear webbing, which is preferably but not necessarily elastic, extends upward and through a wire loop 8 the upper bar of which is held in the upper looped end of the 60 front webbing 4 which is stitched as at 5, the lower bar of this wire loop 8 lying exposed at the rear of the front webbing 4. After passing through said wire loop 8 the narrow rear webbing 7 extends downward 65 and is secured at 9 to the middle cross-bar of a friction buckle 10 upon the narrow rear webbing 7 between its attachment to the end portion 6 of the front webbing and the wire loop 8. By sliding the buckle 10 up and 70 down, obviously the end portion 6 of the front webbing is lowered and raised, respectively, and thus the hose supporter lengthened and shortened accordingly.

At the same time, the narrow rear webbing 75 7, buckle 10, wire loop 8 and the joinings of all the parts, are concealed behind the broad front webbing 4, as shown in Figure 1, and not only a very neat and pleasing appearance secured but also said parts behind the webbing 4 are protected against coming in contact with the dress or outer garments so as to wear the same or show through them in any way, as by causing a protuberance. It is also an advantage of 80 my improved construction that the front and rear webbings together give increased strength to the hose supporter, and make it 85 more durable.

It will be understood that from the lower 90 looped or doubled end of the main webbing 4 is suspended any well-known form of stocking grip, such as indicated by the reference numeral 11, such grip being of course suspended by a wire loop 12 the upper bar 13 95 of which passes loosely through the said doubled lower end of the main webbing 4 so as to be slidably adjustable with respect thereto.

The wire loop 3 which secures the hose 100 supporter to the fabric 2 of the garment 1, I have shown of the safety-pin type, as illustrated more clearly in Figure 4, and it should be noted that instead of the adjacent wire loop 8 which I have described, any 105 other ordinary means for the upper part of the narrow rear webbing 7 to slidably pass over may be employed. Various other details may be modified in manufacturing my improved hose supporter, by those skilled 110

in the art, without departing from the spirit and scope of the invention, and I do not wish to be understood as limiting myself except as required by the following claims when construed in the light of the prior art.

Having thus described the invention, what I claim is:

1. In a hose supporter, the combination of a stocking grip, a front webbing to be attached at one end to a garment and having a 10 slidable engagement with said stocking grip and its other end portion returned toward the first-mentioned end, and a rear webbing adjustable in length connecting said returned 15 end portion of the front webbing to the first-mentioned end.

2. In a hose supporter, the combination of a stocking grip, a front webbing to be attached at one end to a garment and having a 20 slidable engagement with said stocking grip and its other end portion returned toward the first-mentioned end, and a rear webbing adjustable in length connecting said returned 25 end portion of the front webbing to said first-mentioned end, said rear webbing being narrower than the front webbing so as to be concealed thereby in use.

3. In a hose supporter, the combination with means for attachment to a garment, and a stocking grip, of a front webbing extending from said attaching means into slidable engagement with said stocking grip and having an end portion returned toward said attaching means, of a rear webbing 35 secured to said returned end portion of the front webbing and extending into slidable engagement with said attaching means and having a returned end, and an adjustable friction member on said rear webbing be- 40 tween the ends of the front webbing, said

returned end of the rear webbing being secured to said adjustable member.

4. In a hose supporter, the combination with means for attachment to a garment, and a stocking grip, of a front webbing extending from said attaching means into slidable engagement with said stocking grip and having an end portion returned toward said attaching means, of a rear webbing secured to said returned end portion of the front 50 webbing and extending into slidable engagement with said attaching means and having a returned end, and an adjustable friction member on said rear webbing between the ends of the front webbing, said returned end of the rear webbing being secured to said 55 adjustable member at the side thereof away from the front webbing and said adjustable member lying between the front and rear webbings.

5. In a hose supporter, the combination with means for attachment to a garment, and a stocking grip, of a front webbing extending from said attaching means into slidable engagement with said stocking grip and having an end portion returned toward said attaching means, of a rear webbing secured to said returned end portion of the front webbing and extending into slidable engagement with said attaching means and having 60 a returned end, and an adjustable friction member on said rear webbing between the ends of the front webbing, said returned end of the rear webbing being secured to said adjustable member and said rear webbing 65 and friction member being narrower than the front webbing so as to be concealed thereby in use.

ISIDOR ROTH.
